**VISUAL MOTOR COORDINATION
TRAINING DEVICE**

Bernice J. Mayhew, Cleveland Heights, Ohio
(263 Dover Center Road, Bay Village, Ohio 44140)

Filed Nov. 2, 1966, Ser. No. 4,519

Term of patent 7 years

(Cl. D25—1)

FIG.1

FIG.2

FIG. 1 is a perspective view of a visual motor coordination training device showing my new design, and

FIG. 2 is a transverse vertical section taken on a plane indicated by the line 2—2 of FIG. 1.

I claim:

The ornamental design for a visual motor coordination training device, substantially as shown.
